KNITTED PADDING

Frank J. Ford, Worcester, Mass.

Application October 12, 1939, Serial No. 299,163

3 Claims. (Cl. 66—193)

This invention relates to padding formed of fibrous roving. While capable of general application, my improved padding is particularly adapted for use in steam press apparatus for laundries or dry-cleaning establishments, and in other similar machines.

It is the general object of my invention to provide a padding of improved construction, reduced cost and increased durability.

10 A further object is to provide a padding in which a rope of loosely twisted rovings is incorporated as an inlay filler in a knitted structure which possesses exceptional heat-conducting and heat-distributing qualifications, and in 15 which structure the stretch in both directions is in the direction of the arrow 7 in Fig. 4.

20 My invention further relates to arrangements and combinations of parts which will be herein-after described and more particularly pointed out in the appended claims.

A preferred form of the invention is shown in the drawing, in which

Fig. 1 is a side elevation of a portion of a roving rope;

25 Fig. 2 is a plan view of one form of my improved knitted padding;

Fig. 3 is a face view of a portion of the fabric;

Fig. 4 is a back view of a portion of the fabric;

30 Fig. 5 is an enlarged detail face view of a knitted structure;

Fig. 6 is a detail sectional view, taken along the line 6—6 in Fig. 4; and

Fig. 7 is a detail inverted elevation, looking in the direction of the arrow 7 in Fig. 4.

35 In the manufacture of my improved padding, I start with usual textile fibers, such as short-length cotton fibers, and first form the fibers into soft rovings 10. I then assemble a considerable number of the rovings 10 in the form of a loose rope R, in which the rovings 10 extend lengthwise and substantially parallel and with slight twist.

40 I then feed the rope R through a guide or condenser to a knitting machine, preferably of the circular type, and produce a knitted padding therefrom in which the rope R forms fillers or inlays which are firmly bound in place by a plurality of knitting threads. The slight twist in the rope R may be largely removed by the reverse twist feeding motion of the knitting machine.

45 Certain of these knitting threads, as 20, extend circumferentially of the fabric or lengthwise of the ropes R at the face of the fabric, while other threads 21 extend transversely of the ropes

R which they firmly embrace. The threads 21 are interlooped with the circumferentially extending threads 20.

5 Additional threads 22 extend in general circumferentially to form a chain at the back of the fabric and also pass through the fabric to the front side and are interlooped with certain of the circumferential threads 20. The threads 22 thereafter pass downward through the fabric and also shift longitudinally of the ropes R to loop into 10 the next adjacent thread 22. The threads 22 thus provide oblique binders to additionally confine the rovings in the ropes R.

15 After the padding has been thus knit in the form of a tube, the tube is cut longitudinally to produce a broad flat fabric. The knitting threads 20 then extend transversely of the fabric or lengthwise of the ropes R and effectively limit transverse stretch. The knitting threads 21 and 22 permit a slight but definitely limited stretch 20 lengthwise of the fabric or crosswise of the ropes R.

25 I thus provide a padding formed from a soft rope comprising a plurality of loose rovings, but at the same time I provide a padding in which stretch or sagging is definitely restrained, so that the padding is well adapted for commercial purposes.

30 After the fabric is prepared as above described, it is cut in the desired shapes and sizes and the edges are bound in any suitable manner, as by stitching a tape T around the edge, or in some cases, the edge may be finished by overcasting.

35 When used in steam press apparatus, such as is found in laundries and dry-cleaning establishments, my improved pad is found to distribute the heat of the steam very uniformly over an extended area. It is also found that the pad does not as easily burn or char at the point where the steam is injected.

40 While these qualifications particularly adapt my improved pad for use where steam is injected, it may also be used for many other purposes, such as pads for athletic equipment, for upholstery, and in the manufacture of garments and 45 shoes.

45 It will be understood that the particular knitted structure shown may be substantially varied within the scope of my invention.

Having thus described my invention and the advantages thereof, I do not wish to be limited to the details herein disclosed, otherwise than as set forth in the claims, but what I claim is:

50 1. A knitted padding comprising a succession of rope inlays, and a plurality of knitting threads 55

- interlaced with each other to confine said rope inlays and to definitely limit the stretch of the fabric, both longitudinally and transversely of said inlays, certain of said threads extending longitudinally of said inlays at the face of the fabric and crossing other threads with which they are interlooped, and certain of said latter threads forming chains extending transversely of said inlays at the back of said fabric.
2. A knitted padding comprising a succession of rope inlays, and a plurality of knitting threads interlaced with each other to confine said rope inlays and to definitely limit the stretch of the fabric, both longitudinally and transversely of said inlays, certain of said threads extending longitudinally of said inlays at the face of the fabric and crossing other threads with which they are interlooped, and certain of said latter threads forming chains extending transversely of said inlays at the back of said fabric and having inlay-confining portions extending both perpendicularly and also obliquely between said face and back.
3. A knitted padding comprising a succession of rope inlays, and a plurality of knitting threads interlaced with each other to confine said rope inlays and to definitely limit the stretch of the fabric, both longitudinally and transversely of said inlays, certain of said knitting threads extending longitudinally of said inlays at the face of the fabric and crossing other knitting threads with which they are interlooped, certain of said latter threads forming chains extending transversely of said inlays at the back of said fabric and having inlay-confining portions extending both perpendicularly and also obliquely between said face and back, and other of said latter knitting threads forming chains disposed transversely to said inlays and separately encircling and confining each inlay.

FRANK J. FORD. 20
